UNITED STATES PATENT OFFICE.

HIRAM M. BURDICK, OF FRANKFORT, NEW YORK, ASSIGNOR TO EUGENE A. BURDICK.

CLOTHES DRIER.

Application filed June 5, 1926. Serial No. 113,905.

This invention relates to devices extending outwardly from a window or other opening in a building for supporting clothes and other articles while being dried after washing.

It is an object of the invention to provide in such a device a line-carrying frame that may be drawn inwardly of a window or the like so that articles conveniently may be placed upon and removed from the lines by a person inside the building without reaching out and incurring the danger of falling to the ground.

Another object of the invention is to provide a line-carrying frame that normally is wider than the ordinary width of windows in apartment houses and other dwellings, whereby greater capacity is afforded to the device, and that is capable of being narrowed at its inner end to permit it to be drawn through a window or the like inside of a room.

Further, it is an object of the invention to provide a device for this purpose that may be mounted outside of a window or the like without alteration of the building, window frame or sash, and other parts.

When considered with the description herein, the characteristics of the invention are apparent from the accompanying drawings, forming part hereof, wherein an embodiment of the invention is disclosed in association with a window, for purposes of illustration.

Although the disclosures exemplify what now is considered to be a preferable embodiment of the invention, it is to be understood that it is not the intention to be limited necessarily thereto in interpretation of the claims, as modifications and adaptations within the limits of the claims can be made without departing from the nature of the invention.

Like reference-characters refer to corresponding parts in the views of the drawings, of which

Fig. 1 is a side elevation;

Fig. 2 is an outer end elevation;

Fig. 3 is an inner end elevation;

Fig. 4 is a plan view.

In the drawings, A designates frame members, B sash or other closure members of a window or other opening, and C a wall of a building.

The device is supported outside of such an opening by hooks 5 or other suitable attach-

ing means secured in any suitable and relatively high position as in the upper transverse frame member, and brackets 6 therebelow secured to the side frame members or to any other suitable parts of the building. Each bracket has an upstanding pin 7 having a cotter-pin 8 or the like in its upper end.

Outwardly-projecting arms 9 are connected to the brackets by having the upstanding pins of the latter project therethrough, and they are held thereon by the cotter-pins. The outer end of each arm is in the form of a sleeve 10 having set-screws 11. A cross-bar 12, which is a part of the stationary frame of the device, extends through the sleeves and is held associated therewith by the set-screws. The cross-bar is of any convenient length, so that the brackets may be fixed to the wall of a building beyond the frame members of the opening, if desired. Other parts of the stationary frame are hangers 13, depending from the cross-bar, having lower terminal portions 14 projecting toward each other, outwardly-extending substantially parallel rails 15 secured to the hangers above the lower terminal portions thereof, brace-rods 16 secured to the cross-bar and to the rails, and an outer spacing member 17 having downwardly-depending legs 18 secured to the sides of the rails. The outer portion of the stationary frame is supported by chains or ropes 19 secured to the member 17 and engageable with the hooks 5.

The stationary frame is for the purpose of affording a reliable support outside of a building for a movable line-carrying frame. The latter frame includes substantially parallel longitudinal members 20 slidable between the stationary rails 15 on the terminal portions 14 of the hangers 13 and on rollers 21 arranged to traverse those rails. Cross-bars 22 and 23 are secured, respectively, to the outer and inner ends of the members 20, and to the under sides thereof so that they may move under the stationary rails, and they carry pulleys or other suitable line-guides 24 having endless lines 25 associated therewith. The outer cross-bar 22 may be longer than the width of the window or other opening with which the device is associated, in order that a comparatively large number of lines may be carried. The inner cross-bar 23 is of a length less than the width of the opening, so that the line-carrying

frame may be drawn inwardly thereof. In order that the inner end of the movable frame may accommodate as many line-guides as are on the outer cross-bar, the inner cross-bar carries rearwardly-extending lugs 26 in which transverse members 27 are slidable. Each of the members 27 carries a line-guide at its outer end, and has also a depending pin or handle 28 adapted to be 10 grasped by the hand for the purpose of imparting sliding movement thereto. The pins or handles 28 so are positioned that they contact with the end lugs 26 and stop spreading movement of the members 27 when the line-guides thereon are substantially alined with those on the ends of the outer cross-bar 22.

When the device is associated with a window having a vertically-movable sash, it so is positioned that the movable frame may be 20 drawn inwardly under the lower sash when the latter is raised. Before drawing in that frame, the members 27 are contracted, in order that they may clear the sides of the opening. While in its inward position, 25 clothes and other articles may be placed on or removed from the endless lines without the necessity of the operator reaching out of the opening. After the lines have been loaded or unloaded, the frame may be pushed 30 outwardly of the opening, the members 27 spread, and the opening closed. Outward movement of the frame is stopped at the

proper place by contact of the inner cross-bar 23 with the hangers 13, and inward movement thereof is limited by contact of 35 the outer cross-bar 22 with the downwardly-depending legs of the spacing member 18. Tilting of the frame when in the outer position is prevented by contact of the inner cross-bar 23 with the undersides of the stationary rails, and when in the inner position by contact of the outer cross-bar with the under sides of those rails and also by contact of the terminal portions of the hangers 13 with the longitudinal members 20. 45

Having thus described my invention what I claim as new, and desire to secure by Letters Patent, is—

A device of the kind described including a 50 frame attachable to the outside of a wall adjacent to an opening therethrough, and a carrier movable on said frame inwardly and outwardly of the opening and comprising side members, outer and inner cross-bars on 55 said members, rearwardly-extending lugs on said inner bar, transverse members slidable on said lugs crosswise of said carrier whereby their end portion may be extended beyond and contracted within the sides of the opening, and line-guides on said outer bar and 60 said slidable members.

In testimony whereof I affix my signature.

HIRAM M. BURDICK.
